CUTTING TOOL

Fred F. Ruland, Brookline, Mass.

Application July 1, 1938, Serial No. 216,896

7 Claims. (Cl. 164—29)

This invention relates to a cutting tool consisting of a metal punch and die.

One object of my invention is to provide a tool to punch holes in sheet metal by hand which is simpler to use and more certain in attaining desired results than those heretofore known. I am aware that punches and dies to make holes in sheet metal by hand are well known; but they are in several respects unsatisfactory, and it has been 10 my principal object to substantially improve them by having only two separate parts, and so constructing these parts that they interfit and operate in such a manner that the desired holes will correctly be cut out, even though the initial 15 positioning of the punch and die together is not done accurately or the hammering done unevenly.

Another object is to provide such a tool that will shrink or lessen the width of the piece it cuts out so that it will not bind when it is being 20 removed. Still another object is to accomplish the foregoing and other objects with a tool of such construction that is economical and simple to manufacture, and practically certain to attain the desired results even when faultily used.

25 The foregoing and other objects which will appear as the nature of the invention is better understood, may be accomplished by a construction, combination and arrangement of parts such as is disclosed by the drawing and specification.

30 The nature of the invention is such as to render it susceptible to various changes and modifications, and, therefore, I am not to be limited to said disclosures; but am entitled to all such changes therefrom as fall within the scope of 35 my claims.

In the drawing:

Figure 1 is a front elevational view of my punch and die separated.

Figure 2 is a plan view of my die.

40 Figure 3 is a plan view, broken away, showing a piece of metal between my punch and die, ready to have a hole cut in it.

Figure 4 is a front elevational view, partly in section, showing a piece of metal resting on top 45 of the die with the punch directly overhead ready to be placed in position with respect to said die to cut a hole in said piece of metal.

Figure 5 is a sectional view, broken away, showing the punch and die and a piece of metal with 50 a piece cut out of it, leaving a hole, at the completion of the cutting operation.

55 My punch P consists of a main body portion 10 preferably having a flat level bottom surface extending from the outer edge inwardly a short distance. A pilot or centering pin 11 is fixed in

said body portion 10 and projects beyond the end a short distance, terminating in a tapered portion 12. A recess 13 is formed in the lower portion of said body 10, extending inwardly and upwardly into the interior and being preferably of greater 5 depth than the die recess 16 later described.

My die consists of a main body 14 at the top of which is formed a top face outer rim 15, having inner and outer sides which extend straight downwardly therefrom. Extending inwardly 10 from the inner edge of said top face outer rim 15 is a bore or recess 16, adapted to receive the cutting or end portion of said punch P, the bottom, of which recess slants downwardly towards the outside as at 17, terminating at its outside and 15 lowest point, as shown in Figures 4 and 5 of the drawing. Surrounding a hole 20 formed in said body 14 at the center thereof is a boss or raised portion 18 which preferably is substantially level with said top face outer rim 15. Said pilot pin 20 20 fits into said hole 20 and thereby assists in accurately positioning the punch P in said die D. Said boss or raised portion 18 makes it possible to use a short pilot pin 11 which need extend beyond the body of said punch P only a short 25 distance, this extending portion being the tapered part 12 which is thereby enabled to more easily enter said hole 20 should it be mistakenly positioned a little off to one side of said hole 20. Because this extending part of the said pilot pin 30 11 is so short and tapered it is unlikely to be broken or bent should the punch P be struck unevenly or not enter the recess 16 in said die in the position it should during the cutting operation.

35 As will be noted in Figure 5 of the drawing said boss 18 extends into said punch recess 13 during the cutting operation which forms the hole 21, and part of the severed part 22 of the metal sheet M also extends therein because it bends upwardly, which shrinks it in width. As shown in Figure 3 of the drawing, before the punching operation is begun, it is desirable to drill or otherwise make a small hole 23 in the piece of metal M through which said pilot pin 11 may extend and enter said die hole 20.

40 My tool is used by laying a piece of metal M over the top of said die D with the hole 23, that is previously made in said piece of metal M, directly over the hole 20 in said die D, and inserting 45 the said pilot pin 11 through said hole 23 and into said die hole 20. Hammering on said punch P cuts out a hole 21, the middle portion of the cut part 22 being bent so that it slants upwardly 50 towards the center thereof, thereby shrinking its 55

diameter so that it will be slightly smaller than said hole 21 and not bind when being removed back through the hole punched.

By forming said die recess 16 so that its lowest point is outermost, the outside or shearing edge of said punch P will not touch said die at this point, as illustrated in Figure 5 of the drawing, thereby avoiding any likelihood of damaging my tool or locking said punch and severed piece of metal 22 in the said recess 16.

What I claim is:

1. A cutting tool comprising a punch having a recess and having a flat bottom surface of narrow extent adjacent the outer edge of said punch 15 and outside of said recess, and having a pilot pin extending beyond the end thereof, and a die having a hole therein adapted to receive said pilot pin end, and having a recess outside of said hole into which a portion of said punch 20 may enter during the cutting operation, said die having a boss portion outside of said hole, said recess commencing at the termination of said boss portion and slanting downwardly and outwardly evenly to its outermost point.
2. A cutting tool comprising a punch having a flat bottom surface commencing at and extending inwardly from the outside edge and having a pilot pin extending beyond the end of said punch, and a die having a hole therein adapted 30 to receive said pilot pin end, and having a recess outside of said hole into which a portion of said punch may enter during the cutting operation, said die having a boss portion outside of said hole, said recess commencing outside of said boss portion and extending diagonally downwardly and outwardly.
3. A cutting tool comprising a punch having a pilot pin extending beyond the end thereof and having a recess therein extending inwardly from 40 said end, a die having a hole therein adapted to receive said pilot pin end, and having a boss portion outside of said hole and a recess outside of said boss portion into which a portion of said punch may enter during the cutting operation, the maximum depth of said punch recess being greater than the maximum depth of said die recess.
4. A cutting tool comprising a punch having a pilot pin embodying a straight shank portion 50 and a reduced end portion extending beyond the end thereof and having a recess therein extending inwardly from said end, the distance said straight shank portion extends beyond said end being less than the length of said reduced end portion, and a die having a hole therein adapted to receive said pilot pin end, and having a boss portion outside of said hole and a recess outside of said boss portion into which a portion of said punch may enter during the cutting

operation, the distance said pilot pin straight shank portion extends beyond the end of said punch being less than twice the maximum depth of said punch recess.

5. A cutting tool comprising a punch having a pilot pin extending beyond the end thereof and having a recess therein extending inwardly from said end, and a die having a hole therein adapted to receive said pilot pin end, and having a boss portion outside of said hole and a recess outside of said boss portion into which a portion of said punch may enter during the cutting operation, the outside end of said pilot pin being tapered, said tapered portion commencing substantially opposite the deepest point of said die recess when said punch is in cutting position in said die.

6. A cutting tool comprising a punch and a die, said punch having a flat, bottom surface extending inwardly from its outside edge and a recess extending from the inner edge of said surface interiorly into the body of said punch, a pilot pin fixed in the body of said punch having a tapering outer end which extends beyond said surface outwardly, said die having a hole therein adapted to receive said pilot pin, a boss portion adjacent to and surrounding said hole, a recess extending from and around said boss portion into the interior of said die adapted to receive the whole end portion of said punch during the cutting operation, the bottom of said recess slanting downwardly and outwardly in the same angular direction continuously to its terminating point, and a top face outer rim extending inwardly from the outside edge of said die the top surface of which is in a horizontal plane and substantially even with the top surface of said boss portion.

7. A cutting tool comprising a punch and a die, said punch having a flat, bottom surface extending inwardly from its outside edge and a recess extending from the inner edge of said surface interiorly into the body of said punch, a pilot pin mounted in said punch having a straight shank portion that extends beyond the end of said punch a distance less than twice the maximum depth of said punch recess and having a tapering outer end which extends beyond said shank portion, said die having a hole therein adapted to receive said pilot pin, a boss portion adjacent to and surrounding said hole, a recess extending from and around said boss portion into the interior of said die adapted to receive the whole end portion of said punch during the cutting operation, and a top face outer rim extending inwardly from the outside edge of said die having a top surface substantially level with the top surface of said boss portion.

FRED F. RULAND.
